SOD REMOVER

Charles John Philip Smith, 274 Forest Road,
Bexley, New South Wales, Australia

Filed Oct. 12, 1970, Ser. No. 25,427

Claims priority, application Australia Apr. 16, 1970

Term of patent 14 years

Int. Cl. D8—01

U.S. Cl. D8—5

FIG. 1.

FIG. 2.

FIG. 3.

FIG. 6.

FIG. 4.

FIG. 5.

FIG. 1 is a side elevation of a sod remover, showing my new design;

FIG. 2 is a side elevational view of said sod remover seen at right angles to the view of FIG. 1;

FIG. 3 is a view partly in section of said sod remover as depicted in FIG. 2;

FIG. 4 is a plan view taken from below said sod remover;

FIG. 5 is a plan view taken from above said sod remover; and

FIG. 6 is a perspective view with the peripheral plunger element in a lower position.

I claim:

The ornamental design for a sod remover, as shown.
